ERNEST VICTOR STONE, OF LOS ANGELES, CALIFORNIA.

APPARATUS FOR DISTILLING MINERAL OIL.

1,351,266.

Specification of Letters Patent. Patented Aug. 31, 1920.

Application filed November 14, 1918. Serial No. 262,519.

To all whom it may concern:

Be it known that I, ERNEST VICTOR STONE, a citizen of the United States, residing at Los Angeles, in the county of Los Angeles 5 and State of California, have invented new and useful Improvements in Apparatus for Distilling Mineral Oil, of which the following is a specification.

My invention relates to an apparatus for 10 distilling mineral oils.

Considerable difficulty has been experienced in distilling heavy mineral oil having an asphaltic base and containing little or no hydrocarbons of a low boiling point such as 15 gasoline, for the reason that the carbon residue, would in a short time clog up the retorts and the means hitherto in use for keeping retorts free of such carbon residue have proven inefficient.

20 It is an object of my invention to provide an apparatus for subjecting a heavy mineral oil of an asphaltic base to a distillation and cracking treatment in a rotating cylinder provided with means for pulverizing the 25 carbon as it is formed and removing the same from the retort, the process being continuous.

With this and other objects in view, which will appear as the description 30 proceeds, my invention consists in the construction, combination and arrangement of parts constituting my apparatus hereinafter described and claimed.

In the accompanying drawings, which 35 form a part of this specification, I have shown, by way of an example, an apparatus suitable for carrying on my process and in which,

Figure 1 is a longitudinal vertical section 40 of my apparatus, some parts being shown in elevation for clearness of illustration.

Fig. 2 is a cross section taken on line 2—2 of Fig. 3.

Fig. 3 is a cross section taken on line 3—3 45 of Figs. 1 and 2.

Referring to the drawings 10 indicates a cylindrical iron retort provided with suitable means 11 driven by a source of power not shown for rotating the same. The retort 50 is slightly inclined from the horizontal. 12 are suitable roller bearings in front and at the rear of the cylinder. 13 is the head of the oil supply end of the cylinder through which by means of an inlet pipe 14 mounted 55 in suitable bearings 15 on a support 16, the oil is supplied to the retort. 17 is a pipe

leading to the source of mineral oil in communication with the inlet pipe 14. The retort 10 is heated by means of a furnace 18 having side walls 19 which extend upwardly 60 in close proximity to the retort and spaced from the ends thereof. 20 designates an oil burner located within the furnace. 21 is the head of the delivery end of the retort 10, the latter having a cylindrical extension 10', 65 furnishing a bearing face for the rear roller bearing 12. 22 is a vapor outlet pipe passing through the head 21 and which is mounted in a suitable bearing 23 or a support 24. 25 is a vapor pipe connecting the 70 vapor outlet pipe 22 and leads to a suitable condensing apparatus, not shown.

Disposed within the retort 10 is a number of loose iron rods 26 extending approximately throughout the length of the retort 75 chamber which serve to crush and grind the carbon formed therein which owing to the slight inclination of the retort will gradually pass to the vapor outlet end and fall through apertures 27 disposed in a circle in the wall of the retort 10. A pipe 28 is disposed immediately beneath the retort at the place where the carbon delivery openings 27 are disposed for the reception of the carbon. Suitable mechanism such as a scroll conveyor 85 29 removes the carbon from the bottom of the pipe 28.

It is difficult to make an air tight joint closing the apertures 27 during the rotation 90 of the retort 10. I have therefore provided a ring shaped member 30 encircling the retort 10 and covering the apertures 27. At its lower end the ring member 30 is provided with an outlet port 31 which is screw-threaded and in which the end of the pipe 95 28 is seated, holding the ring member 30 in position. The ring member 30 consists of a central ring 32 of a width slightly larger than the diameter of the circular apertures 27 and so disposed that during the rotation 100 of the retort 10, opposite edges of the ring 32 overlap slightly the apertures 27. On opposite sides of the central ring 32 are flanges 33 extending to the outer face of the retort 10 and forming with the central ring 105 32 a pair of annular chambers 34 which are in communication with an annular central steam chamber 35 by means of openings 36 extending at intervals through the lateral walls of the steam chamber 35. The central 110 steam chamber 35 is in communication by means of pipe 37 with a suitable supply of

steam, not shown. It is the object of supplying steam to the annular channels 34 in the ring shaped member 30 so that in place of air steam will enter the retort through the joint formed by the central ring member 32 through the apertures 27 into the retort.

In carrying out my process the heavy mineral oil, preferably preheated, is supplied through pipes 17 and inlet pipe 14 to the retort in a continuous stream. The quantity of oil supplied being controlled by the capacity of the apparatus. The retort 10 is heated to a suitable temperature up to 1000° F. or thereabouts by the furnace 18. The mineral oil is distilled and cracked, the vapors and gases being taken off through outlet pipes 22 and 25, the distillation and cracking being preferably carried out under sub atmospheric pressure. As the retort 10 is rotated the loose iron rods 26 will crush and grind the carbon residue which latter will gradually, due to the inclination of the retort, move toward the delivery end of the retort and pass through aperture 27 into the carbon pipe 28 from the bottom of which it is removed to a suitable place by means of the scroll conveyer 29. The quantity of the mineral oil supplied to the retort must be controlled so that the carbon, as it reaches the delivery end of the retort, will be sufficiently dried to be ground to a powder. The iron rods 26 serve the double purpose of keeping the retort walls free of carbon and at the same time grinding the carbon to a powder so that the same may be readily passed through the aperture 27. The joint 30 providing a chamber of steam about the aperture 27, prevents any access of air to the interior of the retort.

Various changes in construction, arrangement and combination of parts of the apparatus may be made by those skilled in the

art without departing from the spirit of my invention as claimed.

I claim:

1. An apparatus for distilling mineral oils comprising a cylindrical retort slightly inclined lengthwise and rotatably mounted, a pipe for discharging oil into one end of the retort, a second pipe for leading gas from the opposite end of the retort, a furnace for heating the retort, iron rods loosely mounted in the retort so that the rotation of the retort and the tumbling of the rods will grind up the carbon, and means for discharging the carbon from the retort.

2. An apparatus for distilling mineral oils comprising a cylindrical retort rotatably mounted and slightly inclined, rods mounted in the retort to tumble as the retort is rotated, a pipe connected to the upper end of the retort for discharging oil into the retort, a second pipe connected to the lower end of the retort for discharging gas, there being radial outlets through the wall of the retort at the lower end, a ring-shaped member around the retort covering the radial outlets, and a pipe leading from the ring-shaped member and adapted to register successively with the radial outlets to carry away the carbon.

3. An apparatus for distilling mineral oils, comprising a retort rotatably mounted, a pipe for supplying oil thereto, a second pipe for leading gases and vapors therefrom, means for heating the retort, iron rods extending substantially throughout the length of the retort loosely mounted in the retort so that the rotation of the retort and the tumbling of the iron rods will pulverize the carbon, and means for discharging the carbon from the retort.

In testimony whereof I have signed my name to this specification.

ERNEST VICTOR STONE.
